(57) **CLAIM**

The ornamental design for a battery pack, as shown and described.

DESCRIPTION

FIG. 1 is a perspective view of a battery pack according to an embodiment of the present invention;

FIG. 2 is a right side view of the battery pack shown in FIG. 1;

FIG. 3 is a left side view of the battery pack shown in FIG. 1;

FIG. 4 is a top plan view of the battery pack shown in FIG. 1;

FIG. 5 is a bottom plan view of the battery pack shown in FIG. 1;

FIG. 6 is a front elevation view of the battery pack shown in FIG. 1; and,

FIG. 7 is a rear elevation view of the battery pack shown in FIG. 1.

In the drawings, broken lines indicate environmental structure or boundaries that form no part of the claimed design.
